UNITED STATES PATENT OFFICE.

ARTHUR CECIL BUTLER, OF BOSTON, MASSACHUSETTS.

DRAWING MECHANISM.

Application filed July 15, 1924. Serial No. 726,108.

This invention relates to mechanism for drawing rovings, slivers, and the like, and has for its object the production of a mechanism in which a high degree of attenuation of the rovings or slivers may be produced without danger of "bunching" of the short fibers producing irregular yarn.

As commonly constructed drawing mechanism comprises a series of pairs of cooperating rollers through the nips between which the roving passes successively, the pairs of rollers being driven at progressively greater surface velocities in the direction of motion of the rovings. With this construction it is not possible to obtain much of a draft or attenuation of the roving between the intermediate and back pairs of rollers as in case this is attempted the fibers spread and separate too much between the front and the intermediate pairs of rollers.

To overcome this difficulty according to the present invention so as to permit a considerable draft between the intermediate and back pairs of rollers, a normally stationary retarding member is positioned between the intermediate and back pairs of rollers, this member being so formed and positioned relative to these rollers as to impart a frictional drag on the roving over an extended length and to concentrate and condense the fibers and retain any twist which the roving may have so that the roving is put in proper condition for succeeding drawing efforts even though a considerable draft has been effected between the intermediate and back pairs of rollers, the drawing, however, in this arrangement taking place between the retarding member and the intermediate rollers rather than between the retarding member and rear rollers. This drawing member must be so constructed or so arranged that the strand to be drawn bears thereagainst at a distance from the forward feeding mechanism substantially equal to or slightly less than the length of the mass of the fibers of the strand being drawn in such a manner that it holds back the shorter fibers quite similarly to a closely set pair of intermediate rollers with a lightly weighted top roller and causes the drawing out or parting of the fibers to consistently take place at about this point. In common practice heretofore the speed ratios between the rear and intermediate rollers have been of the order of 1 to $1\frac{1}{8}$. According to the present invention

this ratio may well be 1 to 6 or more, so that the draft is about 48 times as much as heretofore. In this way a longer total draft may be obtained without excessive draft between the intermediate and front rollers 60 which is liable to cause uneven yarn.

This retarding member may, if desired, be used in place of the intermediate pairs of rollers of a drawing roving or spinning frame, but by using it in addition to the intermediate rollers a considerable draft may be effected between these rollers and the rear rollers and again a considerable draft between these rollers and the front rollers. It is, of course, necessary that this member 70 be used between two pairs of rollers or other drawing or roving feeding means.

This retarding member may be used with or without a retarding plate. When the plate is used it is sometimes desirable that the retarding member be formed as a plain rotatable rod or shaft as is disclosed and claimed in my application for Patent Serial No. 635,934, filed May 1, 1923 for drawing mechanism, Patent No. 1,554,987 of Sept. 29, 80 1925. It is not, however, absolutely necessary to rotate this member especially when drawing cotton of long staple. When the plate is not used the retarding member should not be rotated.

A further advantage resulting from the use of this retarding member is that it is never necessary, where it is used, to adjust the distance between the intermediate and back pair of rollers to suit the length of 80 staple, this being taken care of by adjusting the member itself toward and from the intermediate rollers which is much easier and simpler than adjusting a pair of rollers. It can also be adjusted closer to the nips between cooperating rollers than can a pair of rollers and is preferably so shaped at its forward edge as to approach partly between the rollers close to their nips. With the use of this drawing member, also, in case a 100 double roving is being drawn, the strands may be caused to lie in superposed relation rather than side by side.

After subjecting the roving or sliver to a considerably longer draft than is usual 105 between the back and intermediate pairs of rollers the positioning of the intermediate and front rollers is such that the fibers after passing through the nip of the intermediate rollers are drawn by the front pair 110

of rollers over or against an arc of the surface of one of the intermediate rollers which serves to prevent the fibers from spreading and also to hold back the short fibers from 5 passing forward with the longer ones until seized in the nip of the front rollers. The surface of one of the front rollers may also be so close to that of one of the intermediate rollers as to further prevent the fibers from 10 spreading acting to smooth and brush them down by its higher surface speed.

Gearing is also provided for these rollers such as to provide for longer total drafts than are customary on spinning or other 15 roller drafting machines and particularly so between the back and intermediate rollers. It also is of such a character that the rollers may be adjusted toward and from each other within the limits in which such adjustment is desirable without requiring any 20 adjustment in the gearing, which remains in mesh throughout all adjustments required.

It also provides a change gear mechanism 25 between the front and intermediate rollers and also between the intermediate and back rollers.

For a more complete understanding of this invention reference may be had to the 30 accompanying drawings in which

Figure 1 is a fragmentary plan of a drawing frame illustrating this invention, the cap bar and upper roller being removed.

Figure 2 is a section on line 2—2 of Figure 35 3.

Figure 3 is a fragmentary top plan of a cap bar and the upper rollers.

Figure 4 is a perspective illustrating a 40 method of effecting traverse of the retarding member.

Figure 5 is a fragmentary perspective view to a much enlarged scale of this member.

Figures 6 and 7 are perspectives illustrating 45 modified constructions.

Figure 8 is a view somewhat similar to Figure 2, but showing a modified construction.

Figure 9 is a section to an enlarged scale 50 on line 9—9 of Figure 10 showing the gearing connections between the various rollers.

Figure 10 is a detail top plan of this gearing.

Figures 11 and 12 are side and plan views, 55 respectively, of a retarding plate which may be used if desired.

Figures 13 and 14 are views somewhat similar to Figures 2 and 8, but showing further modifications.

Figure 15 is a detail perspective of a portion 60 of the construction shown in Figure 14.

Figures 16 and 17 are fragmentary elevations of different forms of retarding bars or members.

Figures 18 and 19 are fragmentary and

end views, respectively, of an adjusting screw.

The retarding member has been shown in Figures 1, 2 and 3 in connection with roller stands having front, intermediate and rear 70 pairs of rollers arranged relatively as disclosed and claimed in my application for patent, Serial No. 635,934, filed May 1, 1923, entitled Drawing mechanism. The combination of the drawing member with rollers arranged in this fashion effects the combination of many of the advantages of the construction illustrated in the above mentioned patent with those of the retarding member of the present invention to produce 80 a highly efficient drawing mechanism, the retarding member causing the strands to be presented to the intermediate and forward pairs of rollers in a condition wherein the advantages of the arrangement of these 85 rollers may be fully realized. The rollers and retarding member are carried by roller stands such as 1 suitably spaced across the drawing frame. To the rear upper edge of 90 the stand is pivoted a cap bar 2 which extends forwardly and adjustable forwardly and rearwardly on its forward end is a block 3 having a slotted guide 4 in which is journaled a front upper roller 5. This roller cooperates with a lower front roller 95 95

6. Back of these rollers are positioned the intermediate rollers 7 and 8, the lower roller 7 being carried by a block 9 adjustable forwardly and rearwardly on the stand 1 and the upper roller being journaled in a slotted

block 3^a adjustable on the forward end of the cap bar 2 and held in position by a bar 10, the rear end of which bears on the rear top roller 11 which cooperates with a lower rear roller 12. The bar 10 is weighted so as 100 to cause the rollers 8 and 11 to engage their corresponding lower rollers with the desired degree of pressure and the front roller 5 is also caused to press against the lower front roller 6. For this purpose a means 110

such as a spring or weight, a spring being indicated at 15, may engage a link 16 hung from an equalizer bar 17 which bears at its opposite ends over rods 18 and 19, the rod 18 at its upper end being hooked over a reduced portion of the roller 5 and the bar 19 being formed to engage the upper face of the bar 10. It will be noted that the front and intermediate pairs of rollers are closely 115 adjacent each other, and that the nip between the front rollers is below the nip between the intermediate rollers and out of the plane thereof. Thus the roving is caused to pass over considerable arcs of the circumference of the lower intermediate roller 7 and the upper forward roller 5,

the extent of which may be varied by adjusting the upper intermediate and front rollers longitudinally of the cap bars, and the block 9 in which the lower intermediate 120

125 roller 7 is journaled. The block 9 is provided with a slot 20 through which the bar 10 may be moved to adjust the pressure of the rollers 8 and 11. The block 9 is provided with a slot 20 through which the bar 10 may be moved to adjust the pressure of the rollers 8 and 11.

The block 9 is provided with a slot 20 through which the bar 10 may be moved to adjust the pressure of the rollers 8 and 11. The block 9 is provided with a slot 20 through which the bar 10 may be moved to adjust the pressure of the rollers 8 and 11.

The block 9 is provided with a slot 20 through which the bar 10 may be moved to adjust the pressure of the rollers 8 and 11. The block 9 is provided with a slot 20 through which the bar 10 may be moved to adjust the pressure of the rollers 8 and 11.

The block 9 is provided with a slot 20 through which the bar 10 may be moved to adjust the pressure of the rollers 8 and 11.

roller 7 is journaled from and toward the lower front roller 6.

Back of the rear rollers 11 and 12 is positioned the traverse bar 20 having roving guides 21 through which the roving is passed on its way to the nip between the rear rollers 11 and 12. Fixed to the traverse bar 20, as shown more clearly in Figure 4, is a downwardly arched bar 22 having its forward end slotted as at 23 for the adjustable reception of a screw 24 threaded into the upper face of a retarding member 25. The bar 22 is downwardly arched to pass beneath the lower rear roller 12 and its forward end is notched to permit the member 25 to be adjustable toward and from the nip between the intermediate rollers 7 and 8. The bar 22 also causes the member 25 to be reciprocated in time with the traverse bar. The member 25 is formed to engage the roving as it passes toward the intermediate rollers and to impart a friction drag thereto acting to prevent bunching of the short fibers and retain any twist there may be in the roving between this member and the rear pair of rollers thus keeping the roving intact so that the draft occurs between this member and the intermediate pair of rollers. It may also be formed to concentrate the fibers so that they may be presented to the intermediate rollers in closely condensed relation. For this purpose or when used for double roving this member may be provided with a guide portion comprising a slot indicated at 26 for each roving or group of rovings passing thereover. The lower wall or base 260 of this slot is formed convex, as indicated clearly in Figures 2 and 5, and the member itself is so positioned as to be above a straight line between the nips of the rear and intermediate rollers so that the roving as it passes through the notch is caused to be drawn down against the convex base 260 whereby a friction drag is imparted to the roving. The side walls 27 of the slot converge in the direction of travel of the roving so that as the roving emerges from the forward end of the slot, the fibers are brought together and condensed. The slot may extend the full width of the member 25 as indicated in Figure 5, or it may terminate back of the forward edge as indicated at 30 in Figure 6, a perforation 31 extending from the forward end of the slot through the forward face of the drawing member. This causes the roving to be condensed in all directions, but has the disadvantage of requiring the roving to be threaded through the perforation 31 instead of being merely laid in the open slot.

A further modification is shown in Figure 7 in which the side walls 32 of the slot are shown as defining a somewhat tortuous channel for the roving so that an increased frictional drag is imparted thereto since it is

held in contact with the side walls as well as with the convex base. Or, if preferred, the friction from the engagement of the side walls might be relied upon entirely. The forward edge of the member 25 is preferably beveled, as shown at 35, so that it may be caused to partially enter between the intermediate rollers 7 and 8 so that the roving may be presented thereby closely adjacent the nip between these rollers. By this means it may be adjusted to suit a very short staple material though it can be adjusted further from the nip of the intermediate rollers when the roving of a longer staple is being drawn.

In Figure 8 an arrangement is shown in which the retarding plate is used in connection with the retarding bar or shaft between the back and intermediate pairs of rollers. This plate is shown in position at 40 in Figure 8 and is shown detached in Figures 11 and 12. While it may take various forms, as illustrated, it is provided with a forward curved portion 41 which may be extended downwardly over the lower intermediate roller 7, the down turned portions 42 being adapted to bear against the rear portion of this roller to retain the plate in position thereon. Back of the portion 41 the plate has a reduced neck portion 43 which connects the portion 41 with a rear wider portion 44 which rests on the upper face of the bar 45. This bar is preferably a round plain rod when the plate is used and may be either plain or provided with grooves as at 46 (Figure 17) or portions of reduced diameter as at 47 in Figure 16 to receive the roving when the plate is not used. The bar 45 may be rotated as disclosed in my application, Serial No. 635,934, hereinbefore referred to or it may be stationary.

In Figure 13 a similar arrangement of rollers and retarding bar is shown, the retarder bar 48, however, being shown as a plain rod or shaft and without a retarder plate resting thereon.

In Figure 14 a still further modification is shown in which the lower intermediate roller 50 has a fluted surface as shown at 51 in Figure 15, and a portion of reduced diameter 52 over which is supported an inverted retarder plate 53 having a weighted portion 54 at one end which holds the portion 53 up against the lower face of the upper intermediate roller 55, this roller being supported on this plate and limited as to its forward position by means of an arm 56 extending upwardly from the support 57 in which the lower intermediate roller 50 is journaled. This support 57 may be adjustable toward and from the forward rollers 5 and 6 in the usual manner. As shown the support is so adjusted by means of a screw 59 threaded through the roller stand and having its end bearing against the forward

face of the support 57. In order that jar-
ring may not cause this screw to loosen and
permit the support to move forwardly, the
rear end of the screw may be formed with
5 flattened oblique faces as shown at 60 in
Figures 18 and 19. The support engaging
on any one of these faces prevents turning
of the screw, due to vibration, as any
turning of the screw would necessarily cause
10 the support 57 to move upwardly and rear-
wardly to permit the high portions 61 be-
tween these faces to rotate. The upper in-
termediate roller 55, as shown, is pressed
against the lower roller independently of
15 the cap bars 2 which support the front and
rear upper rollers by means of a bar 61
having an inclined face 62 riding on a re-
duced portion 63 of the upper intermediate
roller, this bar having a slot 64 at its rear
20 end engaging over the rear upper roller as
shown. This bar 61 may be urged down-
wardly if desired by a suitable weight or
spring (not shown) fixed to the lower end of
a link 65 having its upper end bearing in
25 one of a series of notches 66 in the upper
face of the bar.

In Figures 9 and 10 is shown gearing for
rotating the various rollers. Referring to
these figures, at 70 is indicated a driving
30 gear driven by any suitable source of power.
71 is a gear meshing therewith fixed to a
shaft 72 to which is fixed the lower front
roller 6. On the shaft 72 is journaled a sup-
porting plate 73 through which passes a
35 shaft 74. This shaft 74 carries on one end
a gear 75 meshing with a smaller gear 76 on
the shaft 72 and at its other end the shaft 74
carries one of a pair of change gears 77.
This change gear meshes with a mating
40 change gear 78 on a shaft 79 journaled in a
bracket 80. The plate 73 may be fixed in
proper angular position to cause change
gears of the desired size to be held in mesh
by clamping it to the fixed bracket 730. On
45 the opposite side of the bracket from the
gear 78 shaft 79 has fixed thereto a gear 81
which meshes through an idler gear 82 with
a gear 83 fixed to a shaft 84 to which is
fixed the lower intermediate roller 7. The
50 shaft 84 may move about the axis of the
idler gear 82 as a center and thus the inter-
mediate roller 7 may be adjusted relative to
the forward roller 6 within the necessary
limits without these gears coming out of
55 mesh, even though this motion may not be
exactly about the center of the gear 82 as an
axis. Within the limits of motion necessary
for such adjustment the departures from
this motion are so small as to be negligible
60 in effecting the driving relation between the
rollers.

The bracket 80 is provided with an ar-
cuate slot 90 described about the shaft 79 as
a center and in this slot is adjustable a shaft
65 91 carrying a gear 92 meshing with the gear

81 on the shaft 79. Shaft 91 also carries
one of a pair of change gears 93, the other
change gear being shown at 94 being car-
ried by a shaft 95 to which the rear lower
70 roller 12 is fixed. As the axis of the shaft
95 is eccentric to the axis of the shaft 79 ad-
justment of the shaft 91 within the slot 90
permits various sizes of change gears to be
used as may be desired. If it is desired to
rotate the shaft or rod 48, which, as herein-
75 before pointed out will ordinarily only be
done when a retarder plate is used in con-
nection therewith, this may be effected
through a gear 96 thereon meshing through
an idler 97 with a gear 98 fixed to the shaft
80 95. In case the retarder plate is not desired
these gears 96, 97 and 98 of course may be
omitted.

Having thus described certain embodi-
ments of this invention it should be evident
85 that various changes and modifications
might be made therein without departing
from its spirit or scope as defined by the ap-
pended claims.

I claim:

1. The combination with two pairs of co-
operating roving, feeding and drawing
rollers, of a roving retarding member be-
tween said pairs of rollers, said member
comprising a bar having a slot therein taper-
ing in the direction of feed of the roving and
in which said roving lies, the base of said
slot being convexed and positioned above a
straight line between the nips of the pairs of
rollers, whereby the roving passed through
said nips is caused to bear thereagainst.

2. The combination with two pairs of co-
operating roving, feeding and drawing
rollers, of a roving retarding member be-
tween said pairs of rollers, said member com-
prising a bar having a slot therein tapering
in the direction of feed of the roving and in
which said roving lies, the base of said slot
being convexed and positioned above a
straight line between the nips of the pairs of
rollers, whereby the roving passed through
said nips is caused to bear thereagainst,
means for effecting a traverse of the roving,
and connections from said means to said
member for simultaneously traversing said
member.

3. The combination with two pairs of co-
operating roving, feeding and drawing
rollers, of a roving retarding member be-
tween said pairs of rollers, said member
comprising a bar having a slot therein taper-
ing in the direction of feed of the roving and
in which said roving lies, the base of
said slot being convexed and positioned
above a straight line between the nips of the
pairs of rollers, whereby the roving passed
through said nips is caused to bear there-
against, and means for adjusting said mem-
ber between the nips of said pairs of rollers.

4. In a drawing mechanism three pairs of

drawing rollers between which the roving being drawn is successively passed, means for driving said rollers, the intermediate pair of rollers at a materially greater speed than the rear rollers, and the front rollers at a materially greater speed than said intermediate rollers, and a roving-engaging member positioned between the rear and intermediate pairs of rollers to impart a drafting resistance to the passage of the roving and at a distance from said intermediate pair of rollers dependent on the length of staple of the roving being drawn.

5. In a drawing mechanism three pairs of drawing rollers between which the roving being drawn is successively passed, means for driving said rollers, the intermediate pair of rollers at a materially greater speed than the rear rollers, and the front rollers at a materially greater speed than said intermediate rollers, and a roving engaging member positioned between the rear and intermediate pairs of rollers to impart a drafting resistance to the passage of the roving and at a distance from said intermediate pair of rollers dependent on the length of staple of the roving being drawn, said member having a roving contacting portion formed to condense the roving as it is drawn therewith.

6. In a drawing mechanism, a plurality of roving feeding mechanisms acting successively on the roving with progressively and materially greater velocities in its direction of travel, and a roving engaging member positioned between a pair of said mechanisms and at a distance back of that mechanism next forwardly thereof in the direction of feed of the roving dependent on the length of staple of the roving being drawn and arranged to impart a drawing resistance to its passage.

7. In a drawing mechanism, a plurality of roving feeding mechanisms acting successively on the roving with progressively and materially greater velocities in its direction of travel, and a roving engaging member positioned between a pair of said mechanisms and at a distance back of that mechanism next forwardly thereof in the direction of feed of the roving dependent on the length of staple of the roving being drawn and arranged to impart a drawing resistance to its passage, said member having a roving-contacting-portion formed to condense the roving as it is drawn therewith.

8. The method which comprises subjecting a roving to feeding and drafting actions of materially increasing velocities in its direction of progress and by such drafting action causing its compression or contraction against a relatively stationary intermediary member at or about a point distant from the drafting means relative to the length of the fibers of the roving under treatment, as to

cause the drawing out or parting of fibers to consistently take place at about this point.

9. The method which comprises subjecting a roving to successive feeding actions of materially increasing velocities in its direction of progress, and between successive feeding positions causing it to bear frictionally in a manner to impart a drawing resistance to its passage against a relatively stationary surface located back of the next forward feeding position at a distance dependent on the length of the staple of the roving being drawn to cause the drawing out and parting of the fibers to constantly take place therewith.

10. The method which comprises subjecting a roving to successive feeding actions of materially increasing velocities in its direction of progress, and simultaneously condensing the roving and imparting a drafting resistance to its passage between successive feeding actions and at a distance from the next succeeding action dependent on the length of the staple of the roving being drawn.

11. In a drawing mechanism, a rear pair of cooperating rollers, an intermediate pair of cooperating rollers, a roving retarding member positioned between said pairs of rollers and shaped to impart a frictional drag on the roving and to concentrate the roving adjacent to said intermediate rollers, and a pair of cooperating front rollers having their nips in a different plane from the nip of said intermediate rollers, whereby the roving after passing said member passes over substantial arcs of the circumference of one of each of said intermediate and forward pairs of rollers.

12. A drawing mechanism comprising front and intermediate pairs of drawing rollers, rear roving feeding members, and a stationary member intermediate said intermediate rollers and feeding members and against which the roving is drawn, said intermediate and front rollers being so disposed that the roving is drawn over a substantial arc of one of said intermediate rollers.

13. A drawing mechanism comprising front and intermediate pairs of drawing rollers, rear roving feeding members, and a stationary member intermediate said intermediate rollers and feeding members and against which the roving is drawn, said intermediate and front rollers being so disposed that the roving is drawn over a substantial arc of one of said intermediate rollers and bears over a substantial arc of one of said front rollers.

14. A drawing mechanism comprising forward, intermediate and rear pairs of upper and lower drawing rollers, a cap bar for retaining certain of said upper rollers in position.

sition over their lower rollers, and another upper roller supported in its position independently of said cap bar.

15. A drawing mechanism comprising upper and lower front, intermediate and rear pairs of drawing rollers, a support for the lower intermediate roller adjustable toward and from said front rollers, a cap bar for holding said front and rear upper rollers in operating position, and a member extending from said support for retaining said intermediate upper roller in position.

16. A drawing mechanism comprising front, intermediate and rear pairs of upper and lower drawing rollers, a support for the lower intermediate roller adjustable toward and from said front rollers, a cap bar for holding said front and rear upper rollers in operative positions, a member extending from said support for retaining said intermediate upper roller in position, and a retarder plate bearing on the under face of said intermediate upper roller forward of said lower intermediate roller.

25 17. A drawing mechanism comprising front, intermediate and rear pairs of upper and lower drawing rollers, a support for the lower intermediate roller adjustable toward and from said front rollers, a cap bar for holding said front and rear upper rollers in operative position, a member extending from said support for retaining said intermediate upper roller in position, a retarder plate bearing on the under face of said intermediate upper roller forward of said intermediate lower roller, and a member

against which the roving passes between said rear and intermediate rollers.

18. A drawing mechanism comprising front, intermediate and rear pairs of upper and lower drawing rollers, a support for the lower intermediate roller adjustable toward and from said front rollers, a cap bar for holding said front and rear upper rollers in operating position, a member extending from said support for retaining said intermediate upper roller in position, and a member against which the roving passes between said rear and intermediate rollers.

19. A drawing mechanism comprising front, intermediate and rear pairs of rollers, certain of said rollers being adjustable toward and from certain other rollers, and gearing operatively connecting said rollers throughout the range of adjustment comprising a bracket, a shaft carried by said bracket, one of a pair of change gears on said shaft, a support pivoted about the axis of one of said front rollers, a gear fixed to said front roller, a shaft carried by said support, a gear on said support, a shaft meshing with said roller gear, the other of said pair of change gears being on said support shaft, a gear fixed to one of said intermediate rollers in driving engagement with said bracket shaft and movable relative thereto, and a change gear connection from said bracket shaft to one of said rear rollers.

In testimony whereof I have affixed my signature.

ARTHUR CECIL BUTLER.
